[57] **CLAIM**

The ornamental design for a “hand held buffer for buffing round articles”, as shown.

DESCRIPTION

FIG. 1 is a perspective view of a hand held buffer for buffing round articles showing my new design;

FIG. 2 is a front elevational view;

FIG. 3 is a rear elevational view;

FIG. 4 is a right side elevational view;

FIG. 5 is a left side elevational view;

FIG. 6 is a top plan view; and

FIG. 7 is a bottom plan view;

FIG. 8 is a perspective view of a second embodiment of my design of a hand held buffer for buffing round articles showing a second embodiment of my new design;

FIG. 9 is a front elevational view of my second embodiment;

FIG. 10 is a rear elevational view of my second embodiment;

FIG. 11 is a right side elevational view of my second embodiment;

FIG. 12 is a left side elevational view of my second embodiment;

FIG. 13 is a top plan view of my second embodiment; and,

FIG. 14 is a bottom plan view of my second embodiment.
